[57] CLAIM

The ornamental design for an illuminated contact lens kit, substantially as shown and described.

DESCRIPTION

FIG. 1 is an upper front perspective view of an illuminated contact lens kit showing my new design, the kit being in closed condition;

FIG. 2 is a lower rear perspective view thereof, with the support easel being shown in open or operative position; and

FIG. 3 is an upper front perspective view thereof, the kit being opened in condition for use, the movable light source being shown.

Fig. 1.
